STAPLING MACHINE

William Drypolcher, Valley Stream, N. Y., as-
signor to Lou Obstfeld, Brooklyn, N. Y., and
Abraham I. Obstfeld, Bronx, N. Y.

Application October 27, 1933, Serial No. 695,473

42 Claims. (Cl. 1-3)

This invention relates to stapling machines.

It is an object of the invention to provide a stapling machine in conjunction with which is associated means operable automatically, and simultaneously with the stapling apparatus, to puncture members disposed in connection with the machine. The puncturing operation may be made effective to produce an opening extending entirely through members properly disposed.

10 By such apparatus, the operation by which a member such as a bag is sealed closed also results in the formation in or the association with the bag of means by which the bag may be located and/or supported upon a proper carrier. Application 15 of the invention has been found useful where packages of small articles are sealed closed, to provide, simultaneously with the sealing operation, means by which such packages may be assembled on a display card.

20 For that purpose, in association with the plunger which drives staples through members to be secured together, is carried a punch. On downward movement of the plunger, the punch also moves into position. On a base arranged to receive members to be secured together, are disposed suitable cooperating means for association with both plunger and punch.

25 In one of its specific phases, the invention is applied in association with a stapling machine in which the staples are loaded into the machine by insertion at the end of the machine to which they are fed for their positioning in a securing relationship. In a machine of this type, after the staples have been inserted, a door is moved to a closed position, thus providing a guard for that end of the magazine. By means of such guard, movement of the staples out of the magazine, except when a predetermined series of steps has ensued, is prevented.

30 The punch, in a construction of this type, may be extended immediately in front of this door, a construction which, therefore, normally would interfere with, and even completely bar, access to the magazine. It is an object of the invention to 35 arrange the punch in a manner such that, even though normally the punch may operate for its desired purpose, still, whenever necessary, the several parts may be manipulated so that the punch no longer affects access to the magazine, 40 permitting release of the door whenever desired.

35 In stapling machines of the type here dealt with, staples are carried, side by side, in a magazine; they slide forwardly, step by step, as individual staples are used. It is an object of the 45 invention to provide means for signalling to an

operator the condition of the supply of staples in such a magazine. Generally a slide is disposed in connection with such a magazine, functioning to impel the staples into a position from which they are driven into engaging relationship with the members to be secured thereby. For the purpose here stated, means may be associated with magazine and slide to cause an indication to be given to the operator at the time the number of staples becomes reduced to a point where refilling is necessary. Such an indication is especially desirable since, at the end of the feeding operation, that is, when the slide is moving the last few staples into the vicinity of the plunger, those few staples are hidden from the view of the operator. Since he has no opportunity to determine accurately the condition of the supply of staples in the magazine, he must gauge the moment when refilling becomes necessary.

20 In one type of stapling machine, a magazine, provided for receiving staples to be fed as they are required, is filled through the front end of the machine, the front end of the magazine being left open. Through that open end is effected 25 reloading of the magazine. At that end, in the customary manner, is disposed mechanism for driving individual staples into securing relationship. A proper guard for the end of the magazine may take the form of a door, arranged to define a guide for means such as a plunger which may be made effective for driving the staples into position. It is an object of the invention to provide as, and in association with, such a door, a member of substantial rigidity, not deflecting to 30 any appreciable degree under the action of the apparatus, and providing a guide for staples and plunger of substantially constant dimensions during use. As an element of a construction of 35 this type may be introduced mechanism for maintaining the door closed, which mechanism, in this association, will assure that the door be, at all times, retained in position without any movement until released, not by a pressure against the door itself, but only against the mechanism 40 provided for maintaining the door closed. While a door of this type is, for certain purposes, capable of construction from sheet metal, to assure the properties of rigidity desired, it and the latching mechanism are formed by casting or 45 drop-forging.

50 One specific type of staple described herein has relation to a use for securing together a plurality of members, such as sheets of papers, piled one upon the other. Such a staple generally has a 55

pair of legs which extend through the several layers and are bent or clinched under the bottommost sheet. On many occasions, it is desirable to break down this fixed association by 5 moving the staple. It is an object of the invention to provide a formation of a staple, and a stapling machine for producing such a staple, whereby, after the staple has been driven, by its very formation, it will present means facilitating 10 firmly gripping the staple when it may be desired to remove the staple from an association of the type discussed. Furthermore, the means so formed may be made to provide a hook or similar element for the support of the articles 15 sealed together by the staple. A formation of the character specifically applied for the purposes of this invention has been found especially desirable in connection with staples intended to be in position only temporarily. Such a formation 20 immediately identifies such staples, notifying the user that such a staple was intended to be removed. Where the apparatus may be made effective to impress such an indication into a temporary staple, the machine may have associated mechanism permitting use of the machine 25 for the production of staple formations both of the temporary and of the permanent character.

Staples used commercially usually are supplied 30 in prepared "sticks," that is, the staples are arranged in side by side relationship, and are secured in that relationship by a particular processing or manner of manufacture. In the use of such "sticks," before the staple is driven, it 35 is separated from the "stick." Then there ensues an interval in which the staple stands alone, and is guided to the driving position. If, during that interval, it should, for any reason, be determined not to drive the staple, the staple so 40 separated might affect the mechanism to clog its further operation.

It is an object of the invention to provide 45 means by which a staple so separated will be given support during the period it is being moved by the driving mechanism into engagement with members to be secured thereby, the means being effective so that, if the staple does not complete its movement into engaged relationship, that support will continue, the staple being 50 turned within the apparatus for use on a future occasion. Means for such purpose may take the form of a retractor against which the staple is pressed by the driver, the retractor moving downwardly together with the staple. The construction of the retractor may be such that the 55 staple will be supported upon a ledge so that the staple will have substantially no tendency to move beyond the retractor ledge until the instant at which the staple is being engaged with the members to be secured thereby.

Particular attention will be paid to that type 60 of stapling machine in which the staples are assembled in the magazine by insertion through the end at which the driving plunger is located. In a stapling machine of this character, it is an 65 object of the invention to arrange a slide by which the staples are impelled into position for engagement by the plunger so that the slide is retained in its association with the magazine at 70 all times. Forward impulsion for the slide is secured from a spring housed entirely within the magazine and therein retained. The operation of loading the magazine is simplified to a high degree, the spring being released from the necessary 75 for manipulation during such loading step.

Before staples are inserted into the magazine, the slide is merely retracted to a position at which it is latched. The slide, at no time during use of the machine, becomes separated from the apparatus; it, therefore, can become neither lost nor damaged by separation from the apparatus. The spring itself is out of harm's way, and also is free from the tinkering to which a spring open for manipulation is subjected.

In a stapling machine of the character here concerned, the staples are fed automatically to the driving means. For this purpose, a spring-pressed member may be utilized. It is an object of the invention to house the spring for a stapling machine of the character indicated entirely within the machine, and more especially, within the magazine for retaining the staples for feeding to the driving point.

Such a magazine, due to the fact that the spring is housed therein, and as a result of the operation of the machine itself, is subjected to varied stresses the ultimate result of which may be the distortion of the magazine and the various parts of the apparatus therewith associated. Such a result would carry with it the throwing out of alignment of the various parts of the apparatus, and the consequent inability of the apparatus to function. It is an object of the invention to form a magazine and a body for a machine of the character herein discussed of great rigidity. For this purpose, these parts are made of die-castings or drop-forgings, the bore of the magazine providing the retainer for the spring which then acts against and propels a slide for feeding the staples into driving relationship.

The manner in which the body of the machine is formed provides for the insertion, into the bottom of the casting, of a rigid bar of metal. This bar of metal, so inserted, acts against the 40 walls of the body, rigidifying them along their length. At the forward driving end of the magazine, the bar may be effective in providing a pair of walls, for cooperation with the driving mechanism, to sustain the legs of the staple when it 45 has arrived at the most dangerous stage of the driving operation, that is, when the points of the staple are penetrating the material the staple is to secure together.

It is desired to construct the main body portion of the machine and the magazine of die-cast metal. Since die-cast metal might be too soft to resist the abrasive forces acting when driving staples, it is an object of the invention to associate, with the die-cast body portion, means 55 at the forward end of the magazine to function as positive guides, disposing walls between which and against which each staple will pass and press when being driven and immediately as the staple engages with material to be secured thereby.

In conjunction with a construction of the type here set forth, it is an object of the invention to provide a member which will cooperate with the walls disposed as guides so that a complete path for the staple will be defined. Such member is 65 of rigid metal in which the factor of springiness has been reduced to a small or entirely negligible degree, as, for instance, by drop forging. A member for such purpose may be in the form of a door, as above set forth, and pivoted at a side 70 of the magazine so that it may be swung to contact the end of the magazine and close the same in forming the guide for the staples.

With a construction of this character, the staples are continuously driven against the door by 75

the pressure of the spring coiled in the magazine. If the door be made of resilient material, this continuous pressure, as well as the lateral pressure exerted as the staple is crushed when driven into position, finally will result in bulging the door outwardly and out of the true guide-forming relationship. Consequently, the apparatus will become inefficient as the path of wire staples such as generally used must be accurately dimensioned. Such bulging of the door, by increasing the width of the passage, will destroy the accuracy of alignment between the driving element and the staple when they move together through that passage. With a door constructed in accordance with the invention, and securing means for the door as here described, no such deformation of the door may occur by reason of the rigidity of the member and the manner in which such a member is locked against outward movement and against play. The continued pressure of the staples against the door will be totally without effect.

Doors which have been applied for similar purposes in the past have used elements the resistance of which could be overcome merely by the impact against the staples of the slide when released to impart a substantial shock to the staples. The door of this invention will be unaffected by a shock of that character.

In one type of stapling machine to be considered, there is a magazine and a base, the magazine being pivotally supported upon the base. For such a construction, it is an object of the invention to position a spring between magazine and base to retain the magazine spaced away from the base, with a pivot post made by a simple device such as a pin which will provide, by an interlock between spring and pin, against accidental separation of the pin from the apparatus. Such separation may be effected only by a manipulation of the pin itself into a position other than that which it normally sustains in the apparatus.

Retractors such as here discussed, that is, devices operating in conjunction with the driving means, function to sustain a staple during its downward movement, to keep the staple from falling away from the driving blade during that downward movement, to sustain the body portion of the staple during the driving action, and to counteract tendencies of the staple to bulge downwardly at its intermediate wall portion. The force exerted by a retractor may be resolved into a number of components. One of the components is an upward one; the other is downward, and outward against the door. The first is the one sought. The latter is unnecessary and, in fact, may tend to disalign the staple during its downward movement.

It is an object of the invention to construct a retractor so that the major portion of its force will be upwardly against the staple, and to avoid, to as great a degree as possible, the outward, distorting component. For this purpose, the retractor arm may be bent intermediately thereof to form an upwardly extending shoulder. It is desirable that the retractor, at rest, may not extend up into the path of staples along the magazine. In such position, it may exert an undesired frictional effect against the ready movement of the staples, or may interfere with the operation of loading the magazine with staples through the front end. To guard against this condition, the arm may be provided with a pair

of ears which stop upward movement of the retractor arm, engaging against the bottom face of a channel upon which the staples ride.

Where staples are propelled, as here, toward an end of a magazine through which access is had for refilling or similar purposes, the protection of the user against accidental release of the staples is desirable. It is an object of the invention to provide means to restrain staples within such a magazine against free movement except when certain preliminary steps are taken to effect such freedom of movement. The staples are normally engaged by a device restraining forward movement even against the action of the propelling spring. However, on operation of the driving plunger, the staples are left free to move, being again restrained when the plunger returns to the beginning point for a driving movement.

Other objects of this invention will herein-after be set forth, or will be apparent from the description and the drawings, in which is illustrated a stapling machine capable of effecting certain of the phases of the invention herein set forth.

The invention, however, is not intended to be restricted to any particular construction or arrangement of parts, or to any particular application of such construction, or to any specific manner of use, or to any of various details thereof herein shown and described, as the same may be modified in various particulars, or be applied in many varied relations, without departing from the spirit and scope of the claimed invention, the machine herein illustrated merely showing one manner of practising the invention.

On the drawings, in which the same reference characters refer to the same parts throughout, and in which is illustrated the machine referred to:

Fig. 1 is a view in perspective of a stapling machine embodying features of the invention;

Fig. 2 is a longitudinal vertical cross-sectional view through a machine of the type shown in Fig. 1, parts thereof being shown in elevation;

Fig. 3 is a transverse, vertical cross-sectional view, on the line 3—3 of Fig. 2, but only through the magazine portion of the machine;

Fig. 4 is a horizontal, longitudinal cross-sectional view, on the line 4—4 of Fig. 2, illustrating the door construction, parts thereof being shown in elevation;

Fig. 5 is a detail plan view of a portion of the base including the anvil construction;

Fig. 6 is an enlarged view in vertical cross-section, longitudinally of the machine, of a construction modified to include a staple movement preventing mechanism, only portions of the front end of the machine being illustrated;

Fig. 7 is an enlarged view in cross-section, of details of the preventing mechanism, as seen in a vertical cross-section on the line 7—7 of Fig. 6;

Fig. 8 is a view in perspective of an element of the mechanism;

Fig. 9 is a view in perspective of a modified form of the construction including a punch;

Fig. 10 is an elevational view of a staple as produced by a machine in accordance with this invention under certain circumstances;

Fig. 11 is a detail plan view, illustrating a manner of use for such staples and the punch;

Fig. 12 is an enlarged perspective view of the end of a driving blade; and

Fig. 13 is a view of the detail, partially in section, partially in elevation, illustrating a modified

form of the driving head and anvil of apparatus such as shown in Fig. 9.

On the drawings, a stapling machine 10 is shown as including a base 12, a magazine 14, a driving mechanism 16 and an anvil 18. Base 12 may be a unitary cast structure, whereby a degree of rigidity, necessary to withstand the forces applied by the driving mechanism, is secured. The base includes, at its forward end, section 20 of increased thickness; with this section, the anvil is associated.

Toward the rear of the base, bearings in the form of a pair of lugs 22, through which are formed aligned openings 24, are provided. A pivot post 26 is received through the openings. As a part of the magazine there may be a pair of downwardly extending lugs 28 through which aligned openings 30 are formed, in a similar manner. With lugs 22 and 28 properly related, as here with lugs 28 within the confines of lugs 22, the openings are all brought into alignment. Through the aligned openings is passed post 26, to pivotally mount the magazine upon the base. Lugs 28 may be formed at their rear ends with legs 32, to serve as stops, limiting upward movement to a predetermined level of the forward end of the magazine.

The magazine and casing 34 for the driving mechanism are here made as a single casting 36. At the front end casing 34 is defined; from it extend rearwardly two parallel walls 38 which, at their rear ends, are bonded to each other by a pair of cross-ribs 40 and 42, both of which are spaced apart at bottom 44 of the magazine portion of the casting. The cross-ribs serve to strengthen the casting at this point. A leaf spring 46, inserted through an opening 48 between the ribs, extends rearwardly to the extreme end of the magazine. There it turns upwardly, providing an end wall 50. Portion 52 of the spring, outside the magazine, after passing through opening 48, extends beneath post 26, and then into engagement with top face 54 of the base. In this manner, it is made effective for compelling downward movement of the rear end of the magazine and, therefore, upward movement of its forward end.

Post 26 preferably is notched, as at 56. The spring itself may have a small, upwardly turned lateral lug 58. When the post is in a proper relation, the lug will seat in the notch, thereby restraining the post against lateral play and assuring that the post will not become separated from the apparatus during use. The outer end 55 of the post may be formed with a squared section 60, forming means to grip the post and rotate it. When so manipulated, lug 58 will be cammed out of notch 56, and, therefore, out of the engaged relationship. The post may then be 60 slid outwardly, and thereby be separated from its bearings, liberating the casing and magazine from the base.

Walls 38, at their upper ends, are inwardly turned into flanges 62. Between the bottom ends 65 of the walls is positioned and secured a bar 64. Bar 64 may be secured to the magazine by any desired device, as by rivets 66, to secure the utmost rigidity therefrom. The bar preferably is of considerable thickness; in one form, it is of 70 bar steel, functioning to rigidify the otherwise widely separated walls, together with the ribs. The bar extends to the forward end of the magazine, just beneath casing 34, at which it is cut away in a manner hereinafter to be referred to. 75 Seated upon the bar is a channel member 68

of slightly smaller dimensions than the passage formed by walls 38 and bar 64, the difference being sufficient to provide a guideway 70 for reception of slide 72 and staples 74. Member 68 may be secured to bar 64 in any desired manner, such, 5 for instance, as spot welding.

Within the bore 76 of the channel is housed a coiled spring 78. This spring, at its rear end, is stopped against wall 50; at its forward end, the spring bears against a down-turned leg 80 of an 10 oscillatory member 82 carried by slide 72. The body of the slide itself is preferably of U-shaped construction, having its legs 84 seated within the guideway and its cross-wall 86 riding over flanges 88 of the channel. At its rear end cross-wall 86 15 terminates in a forwardly turned ear 90.

Member 82 may be formed from a stamping, in which case its rearmost extremity may be a finger 92 for insertion beneath ear 90 to retain that portion of the member firmly associated with 20 the slide, while permitting lateral oscillatory movement thereof. Forwardly of the finger, the stamping may be turned upwardly, and then downwardly again, to provide a thumb piece 94 25 by which member 82 may be manipulated.

At its forward end, the stamping is turned down to form leg 80. A slot 96 is formed in cross-wall 86, through which leg 80 passes. Flanges 88, similar to flanges 62, cooperate in defining guideway 70. Leg 80 has a reduced section 98 to permit its extension through slot 100 between flanges 88. By this relationship, the leg is retained against outward movement, the leg within the channel being increased in extent to conform 35 substantially to the effective cross-sectional area of the bore 76.

Staples, positioned in the guideway, are impelled forwardly by spring 78 into cooperation with driving mechanism 16. Closely adjacent the rearmost portion of one flange 62 is provided a 40 notch 102 into which a laterally extending finger 104, formed as a part of thumb piece 94, may, by swinging member 82 laterally, when slide 72 is retracted sufficiently, be engaged. The slide will then be retained against the action of spring 78, making the slide ineffective. When the slide 45 is so retained, the magazine may be loaded without danger that the spring will propel staples out of the magazine and at the person handling the machine. 50

Generally, die metal is relatively soft. For the operations to which apparatus of this character will be subjected, such metal would soon show marked signs of wear to such a degree that the apparatus might become entirely inaccurate. Bar 64, of a hardened metal, functions not only to rigidify the magazine, but also, at its forward end, provides a pair of faces 106 with which other elements cooperate to form guides for the staple during the driving action. The bar, at this forward end, may be cut away at 108, for a purpose hereinafter to appear, leaving lugs 110, the forward ends of which define faces 106. The thickness of bar 64 is substantially that of the height 65 of one of the staples, the purpose being to assure a firm backing wall for the staple immediately at the time that driving and clinching action occurs.

Above lugs 110 is the end of member 68, likewise cut away, with its end edges disposed substantially in the same plane as lugs 110. While these end edges are of small thickness, this is sufficient to define a guide in the period during which the staple is passing the end edges. In that period, no force other than the propelling 70

force is being exerted upon the staple. The end edges merely cooperate with door 112 in defining a passage 114 through which the staple moves in travelling down to the members to be secured 5 thereby.

So that at least the legs of staples, moving through passage 114, may have support to assure downward movement under proper guidance, there is required an accurate alignment of lugs 10 110 and these end edges. To counteract any tendency on the part of the staple to engage against the top edges of lugs 110, and to assure that such engagement will not take place, even with the accurately dimensioned parts used in 15 such apparatus, the top edges of the lugs are bevelled as at 116, providing a cam face for moving the staples outwardly on downward movement.

The ends of member 68 and bar 64 thus define one wall along which a staple rides during its 20 downward movement. These parts, being separate and distinct from the die-casting, may be made of wear resisting, hardened steel. To define the sides of passage 114, means of the same character may be positioned. A pair of plates 25 118 are inserted in recesses 120, cut away in the cast metal, the plates being secured in position between the bar and the cast metal. The plates extend forwardly beyond lugs 110 a distance just sufficient to form a passage 114 of a width to 30 receive snugly the moving staple and the driving means. These plates extend up beyond the top of member 68. Therefore, during the entire time of movement of the staples and when being driven, the plates continuously constitute for 35 the staples a wall having great resistance to wear.

The forward end of the magazine may be closed in any manner so long as this relationship of parts is secured, and so long as passage 114 is maintained properly dimensioned to limit movement therethrough to but a single staple at any one time. In order to permit filling of the magazine through that end at which the staples are separated from the supply and driven into engagement with the members they are to secure, 45 the means provided for closing the end of the magazine preferably is made in the form of a door 112.

The door, for purposes herein stated, may be made by drop forging, assuring great rigidity and 50 resistance to distortion. The door may have a centrally grooved portion 122 from which extend away a pair of faced wall sections 124. At the end of each faced wall section is provided a mounting means, in one case being comprised of a 55 pair of lugs 126 constructed for the reception of a pivot pin 128 carried by lugs 130 at the end of the cast magazine portion. A coiled spring 132 operates normally to rotate the door to open position, the door cooperating with the casting to limit its 60 rotational movement.

At the other section 124 a pair of lugs 134 carry a pin 136, leaving an opening 138 between them. At the associated portion of the cast magazine section there is provided a pivot pin 140. A latch 65 142, pivoted upon the pin, is normally spring-pressed outwardly by a spring 144 engaged between the latch and the wall of a recess 146 in which the latch is seated. The forward end of the latch may include a hook-defining element 148, the extreme outer face of which has a cam surface 150. Element 148 has a recess 152, the walls of which are turned outwardly for a purpose to appear.

When the door is moved to bring pin 136 against

surface 150, the latch will be forced backwardly against the action of the spring in recess 146, finally bringing pin 136 so that it may engage within recess 152. Spring 144 will then force the latch outwardly, the recess partially encompassing 5 pin 136. The latch may be provided with a slightly raised element 154 extending a small distance out of the recess, to function as thumb piece. By pressing on element 154, the latch may be depressed into the recess to release engagement of pin 136 and the latch. When the door is retained closed, staples within the magazine will be driven toward grooved portion 122. Recess 152, by its formation, will be unaffected by such force which will be incapable of separating the pin 15 from its engaged relationship. In fact, increased force will make the recess more positive in its retaining function.

Faced sections 124 seat against the end edges 20 of plates 118 and themselves define the front walls of passage 114. Grooved portion 122, together with the cut-away character of the bar and the channel, all accommodate a retractor 156, associated with the apparatus to support the staple in its downward movement. This retractor preferably consists of side wall sections 158 forming bearings for a pivot pin 160, sections 158 preferably being a pair of lugs formed as an integral part of retractor arm 164. Coiled spring 166 normally forces the retractor upwardly so that the arm will be in engagement with the bottom face of flanges 88.

Arm 164 is angularly deformed intermediately thereof, as at 168, so that its end 170 extends upwardly at a sharper angle than does the section pivotally mounted on the pin. In this manner, the pressure exerted by end 170 will have its greatest, and, preferably, substantially all of its force directed vertically upwardly, eliminating to 40 as great a degree as possible the forward component. With the end bent up in this manner, it might extend into the plane of guideway 10, interfering with proper feeding of staples. A pair of ears 172, formed with the arm, at the upper limit of movement of the arm, abut against the bottom face of flanges 88. In this manner, the top face of end 170 is retained spaced downwardly a proper distance away from guideway 10. The groove between flanges 88, as well as the 50 accessibility provided by cutting away the bar and the member, facilitate any repair that may become necessary by reason of clogging of staples. The entire groove is, by such cutting away, made accessible throughout its entire extent for any 55 such repairs.

Casing 34 provides a guideway 174 for the reception of plunger 176 of the driving mechanism. The plunger includes a cap 178, and a body section 180, united to the cap in any desired manner, and extending within the guideway. Preferably, the body section is bored, as at 182, for the reception of a coiled spring 184, the end of which seats over a nub 186 on bottom wall 188. A side wall 190 of the body is cut away to form a slot 192, this slot being positioned in adjacency to an opening 194 in wall 196 of the casing. A leaf spring 198, retained upon a pin 200, carried between ribs 202 of casing 34, extends upwardly and has a squared section 204 inserted through opening 194. This squared section cooperates with slot 192 to limit upward movement of the plunger, the lower limit of its movement being determined either by the staple when completely driven, by 75

a portion of the casting, or by the upper portion of the slot.

At the front face of the plunger, there is provided a protuberance 206, preferably a pin riveted 5 in the body portion. Upon this pin is intended to be mounted a driver plate 208 of practically the same thickness as the staples which are to be driven. The upper edge of the plate extends up to and in close adjacency to a shoulder 210; 10 the cooperation of the upper edge of the plate and the lower face of the shoulder results in the retention of the plate against oscillatory movement.

The plate, at its lower end, has a reenforcement 15 212 provided thereon, this reenforcement having the character of an additional piece of plate, preferably spot-welded to the first plate, the reenforcement extending slightly beyond the bottom edge of plate 208. When the plate is 20 moved downwardly and is in engagement with a staple, the reenforcement will have engagement with the forward face of the top body portion of the staple, retaining it against movement forwardly into grooved portion 122.

Anvil 18 may be formed with a plurality of clinching surfaces 214 and 216, each of which has a different characteristic in the deformation of the legs of the staples which it produces. In 30 connection with clinching surface 216, here indicated as for temporary purposes, but generally applicable for retaining members together, the anvil has an element 218 raised above the plane surface of the anvil.

When the driving plate forces a staple down 35 and body portion 220 of the staple is pressed against element 218, the staple will be shaped to conform to element 218. The end edges of the driving blade may be cut out, as at 222, to cooperate with element 218, during such driving operation, and with the element, to impart to the staple the humped formation 224 shown in Fig. 10. In the same manner, retractor arm 164 may have a notch 225 cut in its end so that the arm 40 will clear element 218 without damage.

In certain specific applications of such apparatus, element 218 may be found unnecessary, and only cut-out 222 be used, as where staples are to be driven over small objects, such as wire, 45 to retain those objects in association with a cardboard plate or a similar element. In such case, the wire cooperates with the anvil and the cut-out to produce the humped formation 224. This humped formation, where formed by the co-action of element 218 and cut-out 222 without the 50 intervention of wire element, and extending free of the member in which the staple is fastened, may, by making the hump large enough, function as a hanger. Also, such a humped formation provides a handle means by which a so-called 55 temporary staple may be grasped, in order to remove it. Such a device eliminates the danger of breaking finger-nails in separating such staples. The extension of the metal of the staple, 60 produced by this formation of a hump, facilitates 65 breaking the staple, where such is desired to effect separation.

The anvil may be a member 226 having a guide 70 228 at its lower face for reception in a guideway 230 in section 20. By this means, and by means of a slide pin 232 which registers with suitable indentations 234 in the bottom face of member 226, the anvil may be positioned so that either 75 of the clinching surfaces 214, 216 may be made effective.

For certain purposes, it may be desirable to make the plunger operate simultaneously not only to drive the staple but also to punch a hole through members which are so to be secured together. For this purpose, a pivot pin 236 is 5 provided adjacent the top of body 180; upon this pin may be pivotally mounted a punch 238. This punch extends downwardly and is guided by a spring arm 240. When the magazine is brought down against members to be secured together, 10 and then the plunger is depressed, punch 238 will be propelled downwardly with the plunger, sliding through the guide formed by arm 240, and then will cooperate with die 242 in base 12 to punch 15 a hole through the member. Since the punch extends down below or substantially to the same level as plate 208, the lower end of the punch would, at all times, be in front of door 112, and would interfere with accessibility to the front end of the magazine and its loading. Arm 240 is 20 constructed to limit movement of the punch merely in one direction, frictionally restraining it against movement in the other direction. However, the punch, by pushing it sideways, is released from engagement with the spring bar. 25 Then the door may be liberated for access to the magazine.

In order that the position of the end edge of slide 12 be, at all times, known to the operator, especially when the end edge of the slide travels 30 within casing 34 and is no longer visible, means are provided to give warning. The slide may carry a prong 244 which, at a suitable position, will engage a vibratory member 246. When prong 244 passes member 246 and releases it, 35 the member will emit a note of warning so that the operator will understand the apparatus requires reloading.

In conjunction with a staple feeding mechanism of the type indicated, it is desirable to 40 have means provided which, when the door is opened, will restrain the staples against outward movement. This is especially true in connection with a slide which, if inadvertently released might propel a supply of staples through the open 45 door. For this purpose, mechanism 248 is used. Within the body of the casting is formed a recess 250 across which extends a pin 252. Upon this pin is pivoted an arm 254 formed with a ledge 256 against which is engaged a spring 258. Extending upwardly from the ledge is a nub 260 which cooperates with an indent 262 in the top 50 wall of the recess to maintain spring 258 in position.

Lower face 264 of the arm is formed with a 55 plurality of teeth 266. These teeth, by the action of spring 258, are forced into engagement with the top surface 268 of the stick 270 of staples carried on flanges 88. By this construction, the teeth, when in engagement with the staples under 60 the action of spring 258, effect a braking action against movement of the staples forwardly in the direction of the open end of the magazine.

Arm 254 has a cam end 272 at its forward end, 65 the end projecting directly into the path of driver plate 208. The projection of end 272 is into passage 114 through which plate and staple move, but, of course, above that portion through which the staple moves. As the driving plate descends, it first engages surface 274 of cam end 272, forcing the arm and ledge 256 to pivot upwardly, removing teeth 266 out of engagement with the staples. Now the staples may move forwardly under the action of their slide and its spring. The driving plate, descending still further, pro- 70 75 75

jects the staple into the properly secured relationship.

During that period, the first staple of the stick is maintained in contact with the driving plate, but, by reason of the width of the passage, may not enter. As the driving plate is retracted and moves above flanges 88, the staples still remain free of teeth 266, and are propelled so that the first staple is brought into alignment with the passage. If desired the plate may immediately be returned to drive that staple also into engaged relationship. The operations of the driving mechanism will then follow in regular order.

On release of the driving mechanism, the plate will move upwardly beyond surface 274, whereupon spring 258 will drive teeth 266 again into engaging relationship to top surface 268, retaining the stick against forward movement. The staple now will be positioned to be engaged by the driving blade upon its descent; if the door be open, the staples will be restrained against forward movement. To load the magazine, it is merely necessary to push the stick through the magazine front end. The teeth will not prevent movement of the staples into the magazine, but function only to prevent movement of the staples outwardly of the magazine. If it be desired to clear the magazine, the insertion of a tool after the door has been opened away, to engage against end 272, will cause upward movement of the teeth, and release of the engaged staples.

In the construction shown in Fig. 13, in order to assure the proper cooperation of punch 238 and the staple-driving means with the anvil, there is made a part of the anvil and magazine, means for assuring the positive relationship of the part continuously during driving and punching action. This is illustrated in Fig. 13 by the construction of the anvil 276 and the guide 278 carried from the magazine. This guide may be made as an L-shaped member, one leg 280 of which is secured in any desired manner to a bottom face of the magazine. The other leg 282 extends within a slot or a groove 284, the lateral walls 286 of which are spaced sufficiently apart to assure the retention of leg 282 and, therefore, the magazine against any material lateral displacement throughout the vertical movement of the magazine with relation to the base. In anvil 276 is also provided an opening 288 with which will cooperate the punch 238. Also there is carried the die faces 290 against which the staple ends will be pressed during driving. In this manner the punch and staple-driving members are all assured a definite relationship continuously during the driving and punching operations. The leg 282 may also serve as a limit for determining the position of any element placed upon the anvil and thus also of the position with relation to that element of the finally punched hole and the secured staple.

Many other changes could be effected in the particular apparatus designed, and in methods of use set forth, and in specific details thereof, without substantially departing from the invention intended to be defined in the claims, the specific description herein being merely to illustrate an operative embodiment carrying out the spirit of the invention.

10. What is claimed as new and useful is:—

1. A stapling machine including a magazine, the magazine comprising means for receiving a supply of a plurality of staples arranged for feeding along the magazine, and having means for causing movement of the arranged staples toward

one end of the magazine, a casing at the latter end of the magazine, a plunger reciprocable in the casing, means carried by the plunger for selecting a fed staple from the magazine and for moving that selected staple into securing relationship to elements positioned beneath the plunger, and a punch carried by the plunger, the punch being mounted to reciprocate with the plunger but externally of the casing, whereby, when the plunger forces a staple into securing relationship, the punch will form an opening through the elements.

2. A stapling machine including a magazine, the magazine comprising means for receiving a supply of a plurality of staples arranged for feeding along the magazine, and having means for causing movement of the arranged staples toward one end of the magazine, a casing at the latter end of the magazine, a driver reciprocable in and having a head extending from the casing, means carried by the driver for selecting a fed staple from the magazine and for moving that selected staple into securing relationship to elements positioned beneath the driver, and a punch mounted upon the head, the punch being mounted to reciprocate with the driver but through a guide mounted externally of and upon the casing, whereby, when the driver forces a staple into securing relationship, the punch will form an opening through the elements, the guide resiliently engaging the reciprocating punch and providing an opening for passage of the punch, the punch being mounted for movement laterally to a position where it will be ineffective as a punch.

3. A stapling machine including a magazine, the magazine comprising means for receiving a supply of a plurality of staples arranged for feeding along the magazine, and having means for causing movement of the arranged staples toward one end of the magazine, that end of the magazine being made accessible for the passage of staples therethrough in loading the magazine, a casing positioned upon the magazine at the latter end, driving mechanism reciprocable in the casing and carrying means for selecting a fed staple from the magazine and for moving that selected staple into securing relationship to elements positioned beneath the mechanism, and a punch carried by the mechanism, the punch being mounted to reciprocate with the mechanism but in front of the loading end of the magazine, the mounting of the punch being such that it may be moved away from its position in front of the loading end to give access to that end, the punch, when the mechanism forces a staple into securing relationship, forming an opening through the elements.

4. A stapling machine including a magazine, the magazine comprising means for receiving a supply of a plurality of staples arranged for feeding along the magazine, and having means for causing movement of the arranged staples toward one end of the magazine, that end of the magazine being made accessible for the passage of staples therethrough in loading the magazine, a door guarding the open end, a casing positioned upon the magazine at the latter end, driving mechanism reciprocable in the casing and carrying means for selecting a fed staple from the magazine and for moving that selected staple into securing relationship to elements positioned beneath the mechanism, and a punch carried by the mechanism, the punch being mounted to reciprocate with the mechanism but in front of the door, the door being mounted to move across the

path of the punch, the mounting of the punch being such that it may be moved away from its position in front of the door to permit opening thereof and to give access to the magazine for loading, the punch, when the mechanism forces a staple into securing relationship, forming an opening through the elements.

5. A stapling machine including a base, a pivot post on the base, a magazine pivoted on the post, the magazine having means for separating and driving staples fed from the magazine, and a spring engaged between the base and the magazine to maintain the magazine normally raised away from the base, the spring passing beneath 10 the post, the spring having interlocking engagement with the post to prevent axial movement of the post, the interlocking engagement being broken by rotation of the post.

6. In a stapling machine comprising, in combination, a casing, a plunger slidably mounted in the casing, an anvil beneath the casing, means cooperating with the plunger to drive a staple through the casing and against the anvil surface, the staple having at least one leg portion for 20 penetration through superposed members to be secured thereby and a body portion to be seated upon a surface of one of the members, and a projection on said anvil surface operable simultaneously with the clinching of the leg portion 25 through the members to form a hump in the body portion of the staple in spaced relation to said leg portion thereof.

7. In a stapling machine comprising, in combination, a casing, a plunger slidably mounted in the casing, an anvil beneath the casing, and means cooperating with the plunger to drive a staple through the casing and against the anvil, the staple having at least one leg portion for 30 penetration through members to be secured thereby and a body portion to be seated upon a surface of one of the members, said anvil having a projection on its staple-engaging surface and the driving means being formed to permit the driving of a staple upon said surface so that the 35 body portion of the staple will bridge over the projection and thereby be provided with a hump positioned intermediate the ends thereof.

8. In a stapling machine comprising, in combination, a casing, a plunger slidably mounted in the casing, an anvil beneath the casing, and a blade moving with the plunger to drive a staple through the casing and against the anvil, the staple having at least one leg portion for penetration 40 through members to be secured thereby and a body portion to be seated upon a surface of one of the members, said anvil having a projection on its staple-engaging surface and the blade having a cut-out end portion and the anvil having a projection therefrom for cooperation 45 with the cut-out to form a hump in the body portion of a staple positioned intermediate the ends thereof.

9. In a stapling machine comprising, in combination, a casing, a plunger slidably mounted in the casing, an anvil beneath the casing, a blade moving with the plunger to drive a staple through the casing and against the anvil, the staple having at least one leg portion for penetration 55 through members to be secured thereby and a body portion to be seated upon a surface of one of the members, and a retractor for supporting the body portion of a staple during driving movement, the blade having a cut-out end portion and the anvil having a projection therefrom for 60 cooperation with the cut-out to form a hump in 75

the body portion of a staple, the end of the retractor being cut-out to cooperate with the projection.

10. A stapling machine having a magazine for retaining a supply of staples, the magazine comprising a cast member providing a pair of spaced apart walls, the walls being turned toward each other at their upper edges, a bar secured in abutting relation to the walls below their upper edges, a channel member seated within the spaced apart 10 walls and upon the bar to define a staple receiving passage, and a pair of plates secured at the forward end of the bar and extending forwardly thereof substantially the thickness of a staple, the bar being of a thickness such that the staple 15 will bear against the end of the bar and the side faces of the plates when the staple is about to begin piercing members to be secured thereby.

11. In a stapling machine, a magazine for retaining a supply of staples, the magazine having 20 an open end, means at the open end for receiving staples from the magazine and driving them into engaged relation, means in the magazine for forcing the staples to move toward the open end, and a substantially non-flexible, rigid door for 25 closing the open end, the door being hinged at one side of the open end and swinging in front of and up against the open end of the magazine, the operation of bringing the door into abutment with the open end causing engagement and lock- 30 ing thereof against pivoting movement.

12. In a stapling machine, in combination with a magazine for feeding staples to be driven, the magazine including a channel section for supporting and guiding the staples, said channel 35 having inturned upper edge portions, a driver blade, a passage for guiding the blade in its reciprocating movement, the staples being fed to the passage for engagement individually by the blade, and retractor means for supporting a staple 40 during driving movement until the staple has reached substantially the engaged relationship, the retractor means comprising an arm pivoted within and extending beyond the channel section, the arm being bent at an angle to dispose its end portion projecting angularly upwardly when in normal position, the sides of the arm having a pair of projections for abutment against the inturned edge portions of the channel to retain the angularly upwardly projected end 50 portion in proper staple receiving position.

13. In a stapling machine having a magazine for receiving a supply of staples, means for driving the staples into a securing relationship, means for propelling the supply of staples to position a 55 staple for cooperation with the driving means, a toothed member for engaging the supply of staples, the member having an arm extending into the path of the staple-driving means, and means for driving the toothed member into engagement with the supply of staples, the arm being engaged by the staple-driving means to release the toothed member from engagement with the supply of staples when the staple-driving means is operated.

14. The combination with a stapling machine comprising a base, a carriage pivotally supported upon the base, the carriage including a magazine for a supply of a plurality of staples, and driving mechanism for separating and driving 70 the staples into members to be secured, of a punch carried by the mechanism and movable therewith toward the base, and means on the base to cooperate with the mechanism and the punch for simultaneously securing together members po- 75

sitioned on the base and forming an opening through them.

15. The combination with a stapling machine comprising a base, a carriage pivotally supported upon the base, the carriage including a magazine for a plurality of staples, and driving mechanism for separating staples from the supply in the magazine and for driving the staples into interlocked engagement with member supported upon the base, of a punch carried by the mechanism and movable therewith toward the base, and means on the base to cooperate with the mechanism and the punch for securing together the members positioned on the base by means of 10 a staple and for forming an opening through them, the staple and the opening being then arranged in predeterminedly spaced apart relationship.

16. A stapling machine including a magazine, 20 the magazine comprising means for receiving a supply of a plurality of staples arranged for feeding along the magazine, and having means for causing movement of the arranged staples toward one end of the magazine, a casing at the 25 latter end of the magazine, driving mechanism reciprocable in and including a head extending from the casing, means carried by the mechanism for selecting a fed staple from the magazine and for moving that selected staple into securing 30 relationship to elements positioned beneath the mechanism, a guide externally of the casing, and a punch carried by the head, the punch being mounted to reciprocate with the mechanism and through the guide, whereby, when the mechanism 35 forces a staple into securing relationship, the punch will form an opening through the elements.

17. A stapling machine including a magazine, the magazine comprising means for receiving a supply of a plurality of staples arranged for feeding 40 along the magazine, and having means for causing movement of the arranged staples toward one end of the magazine, a casing at the latter end of the magazine, driving mechanism reciprocable in and including a head extending 45 from the casing, means carried by the mechanism for selecting a fed staple from the magazine and for moving that selected staple into securing relationship to elements positioned beneath the mechanism, a guide mounted externally of 50 and upon the casing, and a punch carried by the head, the punch being mounted to reciprocate with the mechanism but through the guide, whereby, when the mechanism forces a staple into securing relationship, the punch will form 55 an opening through the elements.

18. A stapling machine including a magazine, the magazine comprising means for receiving a supply of a plurality of staples arranged for feeding along the magazine, and having means 60 for causing movement of the arranged staples toward one end of the magazine, a casing at the latter end of the magazine, driving mechanism reciprocable in and having a head extending from the casing, means carried by the mechanism for selecting a fed staple from the magazine and for moving that selected staple into securing relationship to elements positioned beneath the mechanism, a guide mounted externally of and upon the casing, and a punch pivotally 65 mounted upon the head, the punch being mounted to reciprocate with the mechanism but through the guide or to be pivoted out of the guide, whereby, when the mechanism forces a staple into securing relationship, the punch will 70 form an opening through the elements.

19. A stapling machine including a magazine, the magazine comprising means for receiving a supply of a plurality of staples arranged for feeding along the magazine, and having means for causing movement of the arranged staples toward one end of the magazine, that end of the magazine being made accessible for the passage of staples therethrough in loading the magazine, a door guarding the loading end, a casing positioned upon the magazine at the latter end, driving mechanism reciprocable in the casing, means carried by the mechanism for selecting a fed staple from the magazine and for moving that selected staple into securing relationship to elements positioned beneath the mechanism, and a punch carried by the mechanism, the punch being mounted to reciprocate with the mechanism but in front of the door, the mounting of the punch being such that it may be moved away from its position in front of the door to give access to the magazine for loading, the punch, when the mechanism forces a staple into securing relationship, forming an opening through the elements.

20. A stapling machine including a magazine, 25 the magazine comprising means for receiving a supply of a plurality of staples arranged for feeding along the magazine, and having means for causing movement of the arranged staples toward one end of the magazine, that end of the magazine being made accessible for the passage of staples therethrough in loading the magazine, a door guarding the open end, a casing positioned upon the magazine at the latter end, driving mechanism reciprocable in and having a 30 head extending from the casing, means carried by the mechanism for selecting a fed staple from the magazine and for moving that selected staple into securing relationship to elements positioned beneath the mechanism, a guide mounted in front of the door, and a punch mounted upon the head, the punch being mounted to reciprocate with the mechanism but through the guide, the door being pivoted to move across the path of the punch, the mounting of the punch being 35 such that it may be moved away from its position in front of the door to permit opening thereof and to give access to the magazine for loading, the punch, when the mechanism forces a staple into securing relationship, forming an 40 opening through the elements.

21. A stapling machine including a magazine, the magazine comprising means for receiving a supply of a plurality of staples arranged for feeding along the magazine, and having means 45 for causing movement of the arranged staples toward one end of the magazine, that end of the magazine being made accessible for the passage of staples therethrough in loading the magazine, a door guarding the open end, a casing positioned upon the magazine at the latter end, driving mechanism reciprocable in and having a 50 head extending from the casing, means carried by the mechanism for selecting a fed staple from the magazine and for moving that selected staple into securing relationship to elements positioned beneath the mechanism, a guide mounted in front of the door, and a punch mounted upon the head, the punch being mounted to reciprocate with the mechanism but through 55 the guide, the door being pivoted to move across the path of the punch, the mounting of the punch being such that it may be moved away from its position in front of the door to permit opening 60 thereof and to give access to the magazine.

for loading, the punch, when the mechanism forces a staple into securing relationship, forming an opening through the elements, the guide resiliently engaging the reciprocating punch and 5 providing an opening for passage of the punch, the punch being mounted for movement laterally through the opening to a position where it will be ineffective as a punch.

22. A stapling machine including a base, a pivot 10 post on the base, a magazine pivoted on the post, the magazine having means for separating and driving staples fed from the magazine, and a spring engaged between the base and the magazine to maintain the magazine normally raised 15 away from the base, the spring passing beneath the post, the post having a kerf formed therein, and the spring having a portion extending within the kerf to prevent axial movement of the post and a portion extending within the magazine 20 forming an end wall of the latter.

23. A stapling machine including a base, a pivot post on the base, a magazine pivoted on the post, the magazine having means for separating and driving staples fed from the magazine, and a 25 spring engaged between the base and the magazine to maintain the magazine normally raised away from the base, the spring passing beneath the post, the post having a kerf formed therein, and the spring having a portion extending within 30 the kerf to prevent axial movement of the post, the kerf having a non-circular surface and the spring portion being forced out of the kerf by rotation of the post.

24. A stapling machine having a magazine for 35 retaining a supply of staples, the magazine comprising a cast member providing a pair of spaced apart walls, the walls being turned toward each other at their upper edges, a bar secured in abutting relation to the walls below their upper edges, 40 a channel member seated within the spaced apart walls and therewith defining a staple-receiving passage, and a pair of plates secured at the forward end of the bar and extending forwardly thereof substantially the thickness of a staple, 45 whereby the staple will be guided by the end of the bar and the side faces of the plates during driving.

25. A stapling machine having a magazine for 50 retaining a supply of staples, the magazine comprising a cast member providing a pair of spaced apart walls, the walls being turned toward each other at their upper edges, a bar secured at and in abutting relation to the walls below their upper edges, a channel member seated within the spaced apart walls and therewith defining a staple-receiving 55 passage, and a pair of plates secured at the forward end of the bar and extending forwardly thereof substantially the thickness of a staple, whereby the staple will be guided by the end of the bar and the side faces of the plates when the staple is about to begin piercing members to be secured thereby.

26. In a stapling machine having a magazine for 60 receiving a supply of staples, means for driving the staples into a securing relationship, means for propelling the supply of staples to position a staple for cooperation with the driving means, and means for frictionally engaging the supply of staples to restrain the staples against the effect of the propelling movement, the restraining 65 means being released from engagement with the supply of staples when the staple-driving means is operated.

27. In a stapling machine having a magazine 70 for receiving a supply of staples, means for driv-

ing the staples into a securing relationship, means for propelling the supply of staples to position a staple for cooperation with the driving means, and a toothed member for engaging the supply of staples, the member being released from engagement with the supply of staples when the staple-driving means is operated. 5

28. In a stapling machine having a magazine for receiving a supply of staples, means for driving the staples into a securing relationship, means for propelling the supply of staples to position a staple for cooperation with the driving means, a toothed member for engaging the supply of staples, the member having an arm extending into the path of the staple-driving means, and means for driving the toothed member into engagement with the supply of staples, the member being released from engagement with the supply of staples when the staple-driving means is operated. 20

29. In a stapling machine, a magazine for receiving a supply of staples, means for driving the staples into a securing relationship, the driving means including a blade for directly engaging the staple as it is being driven, constantly active 25 means for propelling the staples along the magazine and into cooperative relation to the blade for driving, and means for engaging the staples to restrain them against movement under the action of the propelling means, the restraining 30 means being made ineffective on movement of the blade into engagement with a staple.

30. In a stapling machine, a magazine for receiving a supply of staples, means located at one end of the magazine for driving the staples into 35 a securing relationship, a door to close that end of the magazine, the door being movable to permit access to that end of the magazine and normally being urged into access-permitting position, means for retaining the door in end-closing 40 position, the driving means including a blade for directly engaging the staple as it is being driven, constantly active means for propelling the staples along the magazine and into cooperative 45 relation to the blade for driving, and means for engaging the staples to restrain them against movement under the action of the propelling means, the restraining means being made ineffective on movement of the blade into engagement with a staple. 50

31. In a stapling machine, a magazine for retaining a supply of staples, the magazine having an open end, means at the open end for receiving staples from the magazine and driving them into engaged relation, means in the magazine for forcing the staples to move toward the open end, a laterally swinging door for closing the open end, releasable positively engaged means for retaining the door closed, and means for automatically swinging the door to open position to uncover said open end when said positively engaged means is released. 55

32. In a stapling machine, a magazine for retaining a supply of staples, the magazine having an open end, means at the open end for receiving staples from the magazine and driving them into engaged relation, means in the magazine for forcing the staples to move toward the open end, a laterally swinging door for closing the open end, means for biasing the door to open position to uncover said open end, a pin on said door and a latch releasably engaging said pin for holding the door closed against the action of said biasing means. 60

33. In a stapling machine, a magazine for re-

taining a supply of staples, the magazine having an open end, means at the open end for receiving staples from the magazine and driving them into engaged relation, means in the magazine for forcing the staples to move toward the open end, a laterally swinging door for closing the open end, means for biasing the door to open position to uncover said open end, a pin on said door and a latch releasably engaging said pin for holding the door closed against the action of said biasing means, said latch mounted adjacent said open end for movement substantially at right angles to the path of movement of the door to open position.

34. In a stapling machine, a magazine for retaining a supply of staples, the magazine having an open end, means at the open end for receiving staples from the magazine and driving them into engaged relation, means in the magazine for forcing the staples to move toward the open end, and a substantially non-flexible, rigid door for closing the open end, the door being hinged at one side of the open end and swinging in front of and up against the open end of the magazine, and positive means for releasably retaining the door closed when the latter is swung against said open end including a spring-projected latch movable substantially at right angles to the path of movement of the door to open position.

35. In a stapling machine, a magazine for retaining a supply of staples, the magazine having an open end, means at the open end for receiving staples from the magazine and driving them into engaged relation, means in the magazine for forcing the staples to move toward the open end, and a substantially non-flexible, rigid door for closing the open end, the door being hinged at one side of the open end and swinging in front of and up against the open end of the magazine, positive means for releasably retaining the door closed when the latter is swung against said open end, said positive means including a spring-projected latch movable substantially at right angles to the path of movement of the door to open position, and means for automatically swinging the door to open position when said latch is moved to retracted position.

36. In a stapling machine, a magazine for retaining a supply of staples, the magazine having an open end, means at the open end for receiving staples from the magazine and driving them into engaged relation, means in the magazine for forcing the staples to move toward the open end, and a substantially non-flexible, rigid door for closing the open end, the door being hinged at one side of the open end and swinging in front of and up against the open end of the magazine, a pin on the free end of said door, and a spring-projected latch pivotally mounted adjacent said open end provided with a hooked end in position to automatically engage said pin to lock the door when the latter is moved to closed position.

37. In a stapling machine, a magazine for retaining a supply of staples, the magazine having an open end, means at the open end for receiving staples from the magazine and driving them into engaged relation, means in the magazine for forcing the staples to move toward the open end, and a substantially non-flexible, rigid door for closing the open end, the door being hinged at one side of the open end and swinging in front of and up

against the open end of the magazine, a pin on the free end of said door, and a spring-projected latch pivotally mounted adjacent said open end provided with a hooked end in position to automatically engage said pin to lock the door when the latter is moved to closed position, and spring means to automatically move the door to open position when said hooked end is moved out of engagement with said pin.

38. A stapling machine comprising, in combination, a casing, a plunger slidably mounted in the casing, an anvil beneath the casing, means cooperating with the plunger to drive a staple through the casing and against the anvil, the staple having at least one leg portion for penetration through members to be secured thereby and a body portion to be seated upon a surface of one of the members, and means carried by said anvil and plunger, respectively, to form a hump in the body portion simultaneously with the clinching of the leg portion through the members by displacing a part of said body portion in a direction extending substantially at right angles to the plane of said surface.

39. A stapling machine comprising a casing, a plunger slidably mounted in said casing, an anvil having a substantially uni-planar upper surface beneath the casing, means cooperating with the plunger to drive a staple against the anvil, and means to form a hump in the body portion of the staple during the clinching of the latter, said means including a projection carried by said anvil and extending above its upper surface.

40. A stapling machine comprising a casing, a plunger slidably mounted in said casing, an anvil having a substantially uni-planar upper surface beneath the casing, means cooperating with the plunger to drive a staple against the anvil, and means to form a hump in the body portion of the staple during the clinching of the latter, said means including a projection carried by said anvil and extending above said surface and a recessed part operated by said plunger during the clinching of the staple.

41. In a stapling machine, a body portion including a magazine for retaining a supply of a plurality of staples in a predetermined side-by-side relationship for sliding movement along the magazine, a driver at one end of the magazine, a pusher in the magazine for engaging against the end unit of the arranged staples, means for compelling movement of the pusher to slide the staples along the magazine, a member movable with the pusher and a vibratory sound producing member projecting into the path of said movable member for actuation by the latter to produce a sound when the supply of staples in said magazine is low.

42. In a stapling machine, a body portion including a magazine for retaining a supply of a plurality of staples in a predetermined side-by-side relationship for sliding movement along the magazine, a driver at one end of the magazine, a pusher in the magazine for engaging against the end unit of the arranged staples, means for compelling movement of the pusher to slide the staples along the magazine, a member movable with the pusher, and a vibratory member fixed to the magazine and projecting into the path of said movable member for actuation by the latter to signal the condition of the supply of staples in the magazine.

WILLIAM DRYPOLCHER.
